UNITED STATES PATENT OFFICE.

CHRISTIAN LEY, OF GLAUCHAU, GERMANY, ASSIGNOR TO THE FIRM OF ALOS APPARATEBAU, GESELLSCHAFT MIT BESCHRANKTER HAFTUNG, OF GLAUCHAU, GERMANY.

STARTER FOR ELECTRIC MOTORS.

Application filed March 28, 1925. Serial No. 19,099.

To all whom it may concern:

Be it known that I, CHRISTIAN LEY, a citizen of Germany, residing at Glauchau, Germany, have invented certain new and 5 useful Improvements in Starters for Electric Motors, of which the following is a specification.

The present invention refers to a starter for one phase-, two phase-, and three phase- 10 alternating current motors and for continuous current motors, which has the advantage over the starters known heretofore in that between the handle and the contact lever an insulating disk is introduced, which 15 may have any size and be of any thickness for giving a good protection at any strength of current and tension without impairing the insulating effect by screws or bolts, because the connection between the handle and 20 the insulating disk as well as the connection between the contact carrier and the insulating disk is solely produced by coupling or 25 engaging members, which in a manner known per se can be brought out of contact by movement in an axial direction, so that the complete starter can be taken apart and put together again.

In the drawing by way of example a 30 starter is shown.

Fig. 1 is an elevation of a starter parts being shown in section;

Fig. 2 is a plan view of the same.

In the drawings, fixed contact laminations 1 are mounted on a base plate 2, from which 35 rises a fixed spindle 3 having screw-threads at its lower end for nuts 4, by which the spindle 3 is fastened to the plate 2. On this spindle a hand wheel 5 is rotatably mounted, the boss 6 of which has at its lower 40 end a laterally flattened or square part 7. Moreover, on the spindle 3 an insulating disk 8 is rotatably mounted, which by the aid of coupling members or pins 9 engages notches 10 in a cap 11, which at the upper 45 part has a square hole to engage the square part 7 of the hand wheel. The lower face of the insulating disk 8 rests on a movable contact carrier comprising a ring 13 surrounding the spindle at a distance and three 50 radial arms 12 projecting from said ring and adapted to slide with their contact faces 14 over the laminations 1 on the base plate. The ring 13 of the contact carrier 12, 55 is provided with pins 15, which engage in corresponding perforations in the lower sur-

face of the member 8. Within the cap 11 is a spiral spring 16, which bears against the upper surface of the disk 8 and against the lower face of the top wall of the cap 11, which is prevented from moving upwardly 60 by the boss 6 of the hand wheel. When the starter is mounted as shown in the drawing the spring 16 is tensioned. The upward movement of the hand wheel and thus of all members below and engaging one another 65 is prevented by a pin or plug 17 projecting through the upper end of the spindle.

It will be well understood, that, when the pin 17 is removed, first the hand wheel 5 and thereupon the cap 11, the spiral spring 70 16, the disk 8 and the contact carrier 12, 13 can be removed from the spindle one after the other. Nevertheless, when assembled, a good contact pressure will be attained between the contact faces 14 of the arms 12 75 and the laminations 1 at any time.

In the construction shown the laminations 1 are arranged in three groups. Also the insulating disk 8 is provided on its periphery with two more contact pieces 19 80 fastened by screws 18 and connected with one another by a copper bar 20. These contact pieces 19 serve for switching in and out the auxiliary phase. They are connected to the insulating disk 8 and can contact, while rotating therewith, with fixed contact pieces 21, which by the aid of suitably bent springs 22 are attached to angle pieces 23, which are connected by screws between two groups of the laminations 1 to the base 90 plate 2. The current is fed to the laminations 1 and the angular arms 23 by the aid of screws 24 passing through the base plate 2, two nuts 25 being placed on each of these screws for firmly fastening them to the base 95 plate. The rotation of the contact arms 12 is limited by stops 26 in such a manner that each arm is adapted to move only over one group of laminations.

It is not absolutely necessary to fix the 100 spindle 3 as it may also be rotatable together with all the parts mounted thereon, while the base plate 2 is held fast. The divers means for coupling may be constructed in a different manner from that shown, so long 105 as after removing the pin 17 or similar locking means, the divers members can be taken off of the spindle.

The starter as shown and described is 110 well adapted for use in connection with

slide ring motors driven by a onephase alternating current. By replacing the insulating disk 8 by a smaller disk, which is not provided on the circumference with contact faces serving for switching in or out the auxiliary phase the starter is adapted for a slide-ring-motor driven by a threephase alternating current. By switching or shunting off one group of laminations the starter is converted into a twophase-starter.

I claim:

1. A starter for electric motors, comprising, a base plate carrying stationary contacts, a spindle attached to the base plate, a handle, an insulating disk and a contact carrier rotatable about the spindle, the contact carrier including a ring surrounding the spindle at a distance and carrying contact arms for sliding over the stationary contacts, coupling members on the contact carrier for engaging the insulating disk from below, a single centrally arranged spring exerting central pressure on the upper surface of the insulating disk when the starter is assembled, a cap embracing the spring and provided with notches, coupling members on the upper face of the insulating disk engaging the notches in the cap, and

means causing the cap and handle to rotate together.

2. A starter for electric motors, comprising, a base plate carrying stationary contacts, a spindle attached to the base plate, a handle, an insulating disk and a contact carrier rotatable about the spindle, the contact carrier including a ring surrounding the spindle at a distance and carrying contact arms for sliding over the stationary contacts, coupling members on the contact carrier for engaging the insulating disk from below, a single centrally arranged spring exerting central pressure on the upper surface of the insulating disk when the starter is assembled, a cap embracing the spring and provided with notches, coupling members on the upper face of the insulating disk engaging the notches in the cap, and means causing the cap and handle to rotate together, fixed springy contact pieces connected to the base, and contact pieces on the periphery of the insulating disk arranged to contact with the fixed springy contact pieces, rotation of the handle causing simultaneous operation of the contact carrier and of the peripheral contact pieces.

CHRISTIAN LEY.
